UNITED STATES PATENT OFFICE.

ANTHONY EUGENE MAGORIS, OF BINGHAMTON, NEW YORK.

POWDER-BLOWER.

SPECIFICATION forming part of Letters Patent No. 465,484, dated December 22, 1891.

Application filed October 1, 1891. Serial No. 407,406. (No model.)

To all whom it may concern:

Be it known that I, ANTHONY EUGENE MAGORIS, a citizen of the United States, residing at Binghamton, in the county of Broome and State of New York, have invented certain new and useful Improvements in Powder-Blowers; and I do hereby declare the following to be a full, clear, and exact description of the invention, such as will enable others skilled in the art to which it appertains to make and use the same.

My invention relates to that class of powder-blowers in which a rubber bellows is used; and my object is to produce a more durable and effective device than those hitherto in vogue; and to this end my invention consists in the peculiar features and combinations of parts more fully described hereinafter, and pointed out in the claims.

20 In the accompanying drawings, Figure 1 represents a transverse section of my complete invention, and Fig. 2 an exterior perspective view.

The bellows *a* consists of a hollow ball or bulb of rubber, such as ordinarily used in powder-blowers. A circular recess is made in one side of the ball and receives a tubular metallic socket *b*, which projects inwardly and is provided with a lateral circular shield *c*, corresponding in form to the circumference of the ball. The outer surface of the ball is cemented or otherwise hermetically sealed to the under side of the shield. This socket *b* forms the only outlet-orifice and receives a nozzle *d*, having a tapering end provided with a discharge-orifice *e*. The exterior of the opposite end of the nozzle is smooth and fits snugly within the socket *b*. An inverted disk-shaped plate *f* is fastened to the outside of the socket *b*, and a helical spring *g* is attached to the plate. The general outline of the spring is that of an inverted cone truncated at the end farthest from the nozzle. Over this spring and its supporting-plate is stretched a porous powder receptacle or sack, its edges at the top being interposed and fastened between the shield *c* and top of plate *f*, which, together with the rubber bulb, form an air-tight joint. This porous sack is, by preference, made of cloth through which the air can pass, although the sack can be made of any other porous material non-soluble, impervious to the effects

of the powder it is adapted to contain. The material, however, must be of such porosity as to permit the air to pass through, but not 55 the powder, for the purpose of the bag is to prevent the powder from coming in contact with the rubber forming the bellows.

The powder used contains matter which disintegrates and otherwise injures rubber when 60 kept in contact with it, and it is for the purpose of keeping the powder away from the rubber that the cloth or other impervious receptacle for the powder is employed.

When the sack is filled with powder and 65 the bulb allowed to expand, air will be sucked in through the nozzle and porous sack into the air-space around the latter, and when the bulb is compressed the air within is forced out through the pores of the sack and carries 70 the powder with it. In the outward passage of the air the sack is prevented from collapsing and stopping the exit by means of the spring *g*; but the spring and sack can be compressed together with the rubber bulb when 75 the latter is sufficiently indented or compressed at the bottom. The retractile force of the spring makes the latter quickly expand with the bulb as soon as pressure is released. It will thus be seen that the powder is act- 80 ively stirred and prevented from caking or clogging, that there is no valve to get out of order, that the rubber does not become injured and lasts infinitely longer, and that the device is cheap, strong, effective, and durable. 85

It is evident that my invention could be varied in many ways that would naturally suggest themselves to a skilled mechanic. Therefore I do not limit myself to the exact construction shown, but consider myself entitled 90 to all such variations as come within the spirit and scope of my invention.

Having thus described my invention, what I claim as new, and desire to secure by Letters Patent, is—

1. In a powder-blower, a rubber bulb or bellows provided with an outlet-orifice, in combination with a porous sack or powder-receptacle located within the bulb and having its mouth placed over said orifice, said sack being composed of non-soluble material, substantially as and for the purpose set forth.

2. In a powder-blower, a rubber bulb, in combination with a porous expandible and

contractible powder-receptacle located within the bulb and having a common outlet to a discharge-orifice, as and for the purpose set forth.

3. In a powder-blower, a bulb or bellows containing a powder-receptacle composed of

5 porous material, substantially as described.

4. In a powder-blower, a bulb or bellows having a single outlet provided with a socket containing a suitable nozzle, in combination

10 with a powder-receptacle comprising a cloth

sack drawn over a helical spring and having its larger end over the outlet of the bellows, in the manner and for the purpose set forth.

In testimony whereof I affix my signature in presence of two witnesses.

ANTHONY EUGENE MAGORIS.
